TRAP SHOOTING TARGET

Lynvell R. Jordan, Santa Monica, Calif., assignor
to Jack B. Nethercutt, Los Angeles, Calif.

Application March 9, 1950, Serial No. 8,409

Term of patent 14 years

(Cl. D34—5)

To all whom it may concern:

Be it known that I, Lynvell R. Jordan, a citizen of the United States, residing at Santa Monica, county of Los Angeles, and State of California, have invented a new, original, and ornamental Design for a Trap Shooting Target, of which the following is a specification, reference being had to the accompanying drawings, forming a part thereof.

Fig. 1 is a perspective view of a trap shooting target, showing my new design, as viewed from the top and one side; Fig. 2 is a top plan view; Fig. 3 is a side elevation; Fig. 4 is a bottom plan view; and Fig. 5 is a vertical transverse sectional view of the target.

I claim:

The ornamental design for a trap shooting target, as shown.
